UNITED STATES PATENT OFFICE

ANTONIO MATARESSE AND ESTEBAN CENTENARO, OF BUENOS AIRES, ARGENTINA

RAZOR SHARPENER

Application filed January 16, 1928. Serial No. 247,126.

This invention relates generally to razor sharpeners, and has more particular reference to novel means for the preparation thereof.

The invention has for an object the provision of a novel means for the preparation of a razor sharpener, which will be efficient in action, and which can be manufactured and sold at a reasonable cost.

For further comprehension of the invention and of the objects and advantages thereof, reference will be had to the following description and accompanying drawing and to the appended claims in which the various novel features of the invention are more particularly set forth.

Referring to the drawing forming a material part of this disclosure:

Fig. 1 is a perspective view of a razor strop prepared according to our invention.

Fig. 2 is a plan view of a device used for preparing a razor strop constructed according to this invention.

Fig. 3 is a side view thereof.

Fig. 4 is an enlarged fragmentary sectional view taken on the line 4—4 of Fig. 2.

The reference numeral 10 indicates generally a strip of cloth material, preferably felt, which is to be treated by having pressed into the texture thereof, a paste mixed with emery, French mould, that is earth, or soil, crude oil or grease, and a small portion of loose varnish. All these ingredients are well mixed and made into a paste, which when properly applied to the strip 10 substantiates a leather strap. The strip 10 is preferably supported near its ends, indicated in Fig. 1 by the dot-dash lines 11, and in Fig. 3 by the arrows 12. The paste to be applied to the strip 10 may be placed in containers 13 and 13' formed with end projections 14 adapted to support rollers 15, these projections 14 continuing in handles 16 pivoted as at 17 so that when the ends of the handles are forced together the rollers 15 are forced against the strip 14.

Each of the containers are formed with doors 18, locked in closed position by catches 19, and adapted to hold air pressure applied in the container by pipes 20 which are con-

nected to suitable supply means not shown on the drawing. The containers are formed with spouts 21 directed to the strip 10. These spouts 21 may be broader than the strip, and are therefore formed with end adjustments consisting of members 22 rigidly attached to the sides of the spouts and formed with dove-tailed portions 23 engaged with dove-tailed grooves 24 in other members 25 having dove-tailed portions 26 engaged by other members 27. The members 25 are formed with projections 28 engaging in slots 29 in members 22, and the members 27 are formed with projections 30 engaging in slots 31 in members 25, so that the members cannot disengage from each other. The members 27 rotatably engage the ends of adjusting screws 32 threadedly engaged in the sides of the spout 21. By the proper manipulation of screws 32 the width of the spout may be adjusted.

In operation only one container is used at a time, that is, either container 13 or 13'. As illustrated the container 13 is to be used, but the device could have been applied to the strip 14 with container 13' on the top, and then this container would be used. Through one of the pipes 20 air pressure is applied in the top container, and the paste therein is forced through the spout 21 onto the strip 14. Manually operated handles 16 are pressed together so that the rollers 15 exert a pressure on the strip, and the device is pushed back and forth along the strip.

While we have illustrated and described our invention with some degree of particularity, we realize that in practice various alterations therein may be made. We therefore reserve the right and privilege of changing the form of the details of construction or otherwise altering the arrangement of the correlated parts without departing from the spirit or the scope of the appended claims.

Having thus described our invention, what we claim as new and desire to secure by United States Letters Patent is:

1. A device of the class described, comprising containers adapted to hold a paste and air pressure, projections therefrom, rollers mounted in the projections and adapted to en-

gage the sides of a strip of cloth, handles continuing from the projections, said handle being hinged to function in the engaging of the rollers to the strip, air pipes connected to the containers, and adjustable spouts formed in the containers and directed to the strip.

2. A device of the class described, comprising a container for assuming a position above a strap to be coated, a second container for assuming a position below the strap, projections from the containers directed towards each other, rollers mounted on the projections, connected handles connected with the projections, and spouts projecting from the containers towards each other for engaging with opposite sides of the said strap.

3. A device of the class described, comprising a container for assuming a position above a strap to be coated, a second container for assuming a position below the strap, projections from the containers directed towards each other, rollers mounted on the projections, connected handles connected with the projections, and spouts projecting from the containers towards each other for engaging with opposite sides of the said strap, said spouts being arranged for adjustments to change their widths for accommodating straps of various widths.

In testimony whereof we have affixed our signatures.

ANTONIO MATARESSE.
ESTEBAN CENTENARO.
